CLAIM

The ornamental design for a turf repair tool, as shown and described.

DESCRIPTION

FIG. 1 is a top, front, and right side perspective view of a turf repair tool showing my new design;

FIG. 2 is a front elevational view thereof, the rear being a mirror image of that shown;

FIG. 3 is a side elevational view thereof, the opposite side being a mirror image of that shown;

FIG. 4 is an enlarged top plan view thereof;

FIG. 5 is an enlarged bottom plan view thereof;

FIG. 6 is a top, front, and right side perspective view of a second embodiment thereof;

FIG. 7 is a front elevational view of the embodiment of FIG. 6, the rear being a mirror image of that shown;

FIG. 8 is a side elevational view of the embodiment of FIG. 6, the opposite side being a mirror image of that shown;

FIG. 9 is an enlarged top plan view of the embodiment of FIG. 6;

FIG. 10 is an enlarged bottom plan view of the embodiment of FIG. 6;

FIG. 11 is a top, front, and right side perspective view of a third embodiment thereof;

FIG. 12 is a front elevational view of the embodiment of FIG. 11, the rear being a mirror image of that shown;

FIG. 13 is a side elevational view of the embodiment of FIG. 11, the opposite side being a mirror image of that shown;

FIG. 14 is an enlarged top plan view of the embodiment of FIG. 11; and

FIG. 15 is an enlarged bottom plan view of the embodiment of FIG. 11.
